(57) **CLAIM**

The ornamental design for a flowerpot, as shown and described.

DESCRIPTION

1. Flowerpot

1.1 is a top perspective view of a flowerpot showing my new design;

1.2 is an exploded top perspective view thereof;

1.3 is an exploded bottom perspective view thereof; and

1.4 is a bottom plan view thereof.

The broken lines on the material around the top edge of the flowerpot in 1.1, 1.2 and 1.3 represent stitching and form a part of the claimed design. The broken lines on the bottom and lower container of the flowerpot in 1.2, 1.3, and 1.4 are included to show features that form no part of the claimed design.
